UNITED STATES PATENT OFFICE.

FRANCIS J. PLYM, OF NILES, MICHIGAN, ASSIGNOR TO THE KAWNEER COMPANY, OF NILES, MICHIGAN, A CORPORATION OF MICHIGAN.

BULKHEAD STRUCTURE AND THE LIKE.

Application filed March 13, 1926. Serial No. 94,374.

The present invention relates to structures usually termed bulkheads and more particularly of the type used in connection with store windows and the like.

5 Among the objects of the invention is to provide a novel bulkhead structure of rigid and unitary construction; one free of contraction and expansion under the varying climatic temperatures; one free from swelling, cracking, warping, sagging, bowing, and other like defects peculiar to wood and other like fibrous material and resulting from humidity conditions; one that is fire-proof, 10 water-tight, non-corrodible, and practically indestructible, as well as acting as an efficient fire stop; one that is rigid, solid, 15 strong and permanent, and yet having a beautiful and attractive appearance; one having means for ventilating and also transmitting light to the space beneath the window floor or the like; and one that can be readily, quickly and cheaply assembled and built.

In a specific embodiment illustrating the 20 invention, the bulkhead is preferably of a single, integral piece of concrete or concretionary material, and this may or may not be covered by or clad with sheet metal facings or the like. When using claddings, the 25 shapes and sizes thereof are preferably such as to afford ready assembling of the parts to form spaces therebetween in which the concretionary material may be poured and allowed to set or harden, thus forming the 30 structure in place, the facings or claddings preferably forming a permanent part of the structure and giving an attractive and beautiful appearance, besides acting as the pouring form for the material of the structure. 35 Where claddings are to be omitted, pouring forms of any suitable nature may be used and later removed. It is to be understood 40 that the invention is not limited to the use of concretionary material nor to the use of claddings, but comprehends the use of any other filling material that may be located in or packed in the spaces formed by the pouring forms or the facings or claddings, and around the connecting parts. 45 As another object, the invention comprehends a structure that will prevent the warping, 50 sagging, distorting and disaligning of the window sash supporting the pane of glass or the breaking of the pane of glass, thus giving 55 the glass a solid and secure foundation.

or support which is free from expansion, contraction, twisting, warping or the like, usually peculiar to wood and like constructions.

The invention also comprehends the forming of the structure with passages or openings for the ventilation of the space below the floor and also for the transmission of light, windows, grids, grilles and the like being preferably provided at the openings or 60 passages, such as at the inner and outer ends of such passages, for controlling the same.

Other objects, advantages, capabilities and features are comprehended by the invention as will later appear and are inherently possessed thereby.

Referring to the drawings, Fig. 1 is a view in front elevation with parts broken away and shown in section of a bulkhead construction built in accordance with the invention.

Fig. 2 is a horizontal sectional view taken in a plane represented by line 2—2 in Fig. 1 of the drawings.

Fig. 3 is a vertical transverse section taken 80 in a plane represented by line 3—3 in Fig. 1 of the drawings.

And, Fig. 4 is a view similar to Fig. 3 of another embodiment of the invention.

Referring now more in detail to the drawings of the embodiments selected to illustrate the invention, one is shown as comprising inner and outer sheet metal wall facings 1 and 2 provided at intervals with opposed or aligned openings 3 and 4, with the walls at 85 such openings provided or formed with inwardly directed or projecting flanges 5 and 6 surrounding such openings, the flange 5 having a bent back portion 7 and the flange 6 having a bent in flange portion 8 as clearly 90 shown in Figs. 2 and 3 of the drawings. To these bent portions of the flanges are connected transverse hollow members 9 having end flanges 10 and 11 which flange 10 has an inwardly directed flange portion 12 fitting 95 into the channel formed by the bent back portion 7 of the flange 5, and the flange 11 having a bent back portion 13 forming a channel for the reception of the flange portion 8 of the flange 6. In this way the ends 100 of the hollow members are locked and sealed with the flanges of the rear or inner facing or cladding 1 and the outer or front facing or cladding 2, thus holding these facings in spaced relation and also providing spaces be- 105 110

tween the hollow members 9. These hollow members may be of any desired shape, as rectangular, or other forms as desired.

The facings 1 and 2 are preferably provided at their upper and lower edges with inwardly directed flanges 14, 15, 16 and 17 as clearly shown in Fig. 3 of the drawings.

These parts of sheet metal or the like may be supplied in standard sizes and forms, and 10 assembled to any dimension of window and may be readily assembled in place as shown. When so assembled, the space between the front and rear walls and around the tubular members 9 may then be filled or packed 15 with any desired filling material, or filled by pouring concretionary material, such as concrete and the like, into such spaces. To effect this result, the sheet metal parts in assembled forms are preferably supported 20 upon a sill or other like foundation 18 and may also, if desired, carry wood strips 19 and 20 to which the floor 21 may eventually be secured, as by nails or screws when a wooden floor is being used. Other floors 25 may be used such as tile, stone, brick or the like, in which even the strips 19 and 20 may be omitted. The concretionary material 22 may then be poured and leveled with the top 30 surfaces of the members 19 and 20, or other given level, and when the same has set and hardened, the window sash 23 and the pane 24 carried thereby may be assembled in place with the sash resting upon the flange 16.

At the inner side of the casement, the inner facing may continue upwardly and inwardly to form a continuous ceiling facing or cladding 1^a as clearly shown in Fig. 3 of the drawings. The material 22 above this facing may be reinforced by any suitable means 22^a, such as wire, rods, mesh fabric and the like, and to hold the facing in place suitable anchors 1^b may be carried thereby and imbedded in the material 22 as shown in Fig. 3 of the drawings.

45 From the above it will be apparent that the bulkhead is of a single unitary and integral construction with the sheet metal or other facings forming a permanent part thereof, and being solid and free of all the disadvantages and defects of prior constructions, and will form a very efficient and advantageous support for the glass window and floor.

The hollow members 9 are provided for the purpose of either permitting the passage 50 of air for the ventilation of the space beneath the floor 21 or for the transmission of light or both. The openings at the ends of the hollow members, such as the openings 3 and 4 may be provided with suitable closing members such as grilles, grids, or windows. In the form shown, the inner opening 3 has a window 25 of sheet metal sash construction and a glass 26, this window being held 55 in place by a hinge 27 secured to the sash of the window and also to the wall 1. Any

suitable means may be used for holding the window in latched condition.

At the other end of the hollow member 60 may be provided any suitable means such as a sheet of material 28 either of transparent characteristics or provided with suitable openings or slots for the passage of air and the like. This member 28 may be secured to the flanges 11 as desired as by screws or bolts 29.

75 While the embodiment above described comprehends claddings or the like, the invention may comprehend the construction of a casement without such facings, claddings and hollow members, except possibly 80 to as formers which may be removed when the material 22 has sufficiently hardened to stand alone. Such a structure is shown in section in Fig. 4 and as comprising reinforcing means 22^a of any suitable form, and 85 having passages 9^a for the transmission of light or air or both, the material 22 being mounted upon a sill 18. Instead of using metal facings at the exterior, facings 2^a of 90 tile, marble, stone, brick and the like or other suitable facing material may be used. Preferably, these facings are provided with openings opposite the outer ends of the passages 9 for the reception of grids, grates, grilles, or 95 transparent members 28^a held in place by 29^a, such as expansion bolts and sockets 29^b, the latter being imbedded in the material 22 as shown.

100 While I have herein described and upon the drawings shown a few illustrative embodiments of the invention, it is to be understood that the invention is not limited thereto but may comprehend other constructions, details, arrangements of parts and features 105 without departing from the spirit thereof.

105 Having thus disclosed the invention, I claim:

110 1. A bulkhead structure for store windows comprising a sill or other solid foundation, a monolithic concrete wall supported from said sill and having a transverse passage therethrough, the inner and outer surfaces of said wall and passage being covered with sheet metal and a window floor and window located above and supported by 115 said wall.

120 2. A bulkhead structure for store windows comprising a sill, a monolithic concrete wall supported from said sill and having a transverse passage therethrough, a window and window floor above and supported by said wall, the inner and outer surfaces of said wall being faced with sheet metal, the surfaces of said passage being faced with sheet metal and means for connecting the metal faces of the passage to the faces of the inner and outer surfaces of 125 the wall.

130 3. A bulkhead structure for store windows comprising a sill, a monolithic con-

- crete block supported by said sill, a window sash and window pane mounted on the upper portion of the front wall of said block, said block having a transverse passage therethrough, sheet metal claddings for the front and rear of said block and for the surfaces of the transverse opening, said claddings having interconnecting flanged portions. 5
4. A bulkhead structure for store windows comprising a sill and a monolithic concrete block thereon having a transverse opening for light and air, said block having a rearward overhanging extension, and a window and window floor mounted on and supported by said block and rearward extension. 10
5. A bulkhead structure for store windows comprising a sill and a monolithic concrete block supported thereon and having a transverse opening for light and air, said block having a rearward overhanging extension, a metallic reinforcing through said block and extending longitudinally through said rearward extension, a window sash and pane mounted upon the front of said block and a window floor mounted upon the top of the block and rearward extension. 15
- 20
- 25
6. A bulkhead structure of store fronts comprising a supporting sill, a monolithic concrete block supported thereby and provided with a transverse opening, said block having an overhanging rearward extension, a window and window floor mounted upon said block and extension, the front and rear faces of said block having sheet metal claddings, said rear cladding extending over the bottom face of said overhanging extension of the block. 30
- 35
7. A bulkhead structure for store fronts comprising a supporting sill, sheet metal casings having front and rear faces and interconnected transverse members forming a passage through said casings, said casings being supported upon said sill, and concrete poured into said casings to form a solid monolithic block upon said sill having adherent metal clad exterior front and rear
- faces and passage faces, and a window sill and window floor mounted upon the upper 50 face of said poured block.
8. A bulkhead structure for store windows comprising a sill and a monolithic concrete wall poured in position upon said sill and formed with a transverse passage therethrough for light and air, and a window and window floor mounted upon said wall. 55
9. A bulkhead structure for store windows comprising a foundational support, a poured concrete wall mounted upon said sill and provided with a rearwardly overhanging integral portion, a window and a window floor supported by said wall and rearward extension, said wall having a passage for permitting the entry of light and air 60 and means at the outer end of said passage for closing the same. 65
10. A bulkhead structure for store windows comprising a foundational support, front and rear sheet metal members, provided with opposed openings, hollow sheet metal members connected to said front and rear members at said opening to form passages through the structure and also to form a pouring space about said hollow members 70 and between said front and rear members, poured concretionary material in said space and forming a single rigid mass, said members and said mass forming a rigid unit, a window and window floor mounted upon 75 said unit, and means secured in the ends of said hollow members for closing said openings while permitting transmission of light through said structure. 80
11. A bulkhead structure for store windows comprising a foundational support or sill, a concrete monolithic wall on said support and having a transverse opening therethrough for the passage of light therethrough, and a window sash and window 90 floor mounted upon and supported by the upper surface of said wall.

In witness whereof, I hereunto subscribe my name to this specification.

FRANCIS J. PLYM.
